Patented June 14, 1921.

UNITED STATES PATENT OFFICE.

ISIDORE STARR, OF NEW YORK, N. Y.

PICTURE-FRAME.

1,381,762.

Specification of Letters Patent. Patented June 14, 1921.

Application filed November 27, 1920. Serial No. 426,699.

To all whom it may concern:

Be it known that I, ISIDORE STARR, a citizen of the United States, and a resident of the city of New York, borough of the Bronx, in the county of Bronx and State of New York, have invented a new and Improved Picture-Frame, of which the following is a full, clear, and exact description.

10 This invention relates to improvements in picture frames, an object of the invention being to provide a frame which includes a pair of transparent faces adapted to expose both sides of a sheet located between them.

15 A further object is to provide a frame having a hinged or detachable member at one side which may be removed to permit the entrance or withdrawal of a picture.

20 A further object is to provide a frame including two identical faces, one which will be neat and attractive in appearance, simple in construction, strong and durable in use, and comparatively inexpensive to manufacture.

25 A still further object is to provide improved means for removably locking the frame against opening when a picture is located therein, and to provide improved suspension means which will permit the frame to be readily turned to expose either side thereof.

30 With these and other objects in view the invention consists in certain novel features of construction, and combinations and arrangements of parts, as will be more fully hereinafter described and pointed out in the claim.

In the accompanying drawings—

35 Figure 1 is a view in front elevation of my improved picture frame.

Fig. 2 is a view in rear elevation thereof.

Fig. 3 is a view in transverse section through the frame.

40 Fig. 4 is an enlarged broken face view of the upper end of the frame, parts of the locking device being broken away for clearness.

Fig. 5 is an edge view of Fig. 4.

45 Referring in detail to the drawings, 1 represents a rectangular frame preferably formed of metal. The frame includes inwardly extending flanges 2 forming channels. Three sides of the frame are permanently connected in any approved man-

55 ner, but the fourth side 3, preferably the top side of the frame, is hingedly connected at one end to the adjacent frame member as shown at 4. This hinged frame member may be swung open as indicated in dotted lines in Fig. 4 to permit the insertion of 60 a pair of transparent plates or sheets 5 within the frame. The sheets 5 are ordinarily of glass and are held in place by the flanges 2. The article to be exhibited, 6, is located between the sheets 5. I have illustrated a discharge certificate from the 65 United States Marine Corps in position in the frame.

The free end of the hinged member 3 is provided with any suitable means for removably locking with the adjacent frame member. I have illustrated an apertured 70 spring tongue 7 on the member 3 engaging with a stud 8 on the adjacent frame member to lock the parts together.

75 Alined eyes 9 extend laterally from the sides of the frame and receive the ends of a flexible suspension device 10. The flexible device 10 has its intermediate portion located over a nail or other support 11 80 projecting from a wall.

The frame is supported on the nail with the front face of the discharge certificate exposed. If it is desirable to examine the service record on the back of the discharge 85 certificate the frame may be turned, twisting the flexible device around the nail as shown at 10. On the other hand if it is desirable to permanently expose the service record the device may be removed from its 90 support, passed through the flexible device, and hung up with the service record exposed, the position of the eyes 9 permitting this operation.

95 The frame is not necessarily limited to its use as a display device for discharge certificates. It forms an attractive frame for any picture and is especially convenient for displaying well known pictures which have their history printed on their back.

100 Various slight changes might be made in the general form and arrangement of the parts described without departing from the invention, and hence I do not limit myself to the precise details set forth but consider myself at liberty to make such changes and alterations as fairly fall within the spirit and scope of the appended claim.

I claim:

A rectangular frame, a pair of transparent plates mounted in the frame and adapted to support between them an opaque sheet having printed matter on both of its faces, alined eyes projecting laterally from the sides of the frame and a flexible device having its ends secured to the eyes, whereby when said flexible device is suspended from a support, said frame may be 10 rotated upon said flexible device to expose either face without removing the flexible device from its support.

ISIDORE STARR.
